Philippss(74) *Attorney, Agent, or Firm* — Reilly Intellectual Property Law Firm(57) **CLAIM**

The ornamental design for a mixing pump impeller vane assembly, as shown and described.

DESCRIPTION

FIG. 1 is a front perspective view of a mixing pump impeller vane assembly;

FIG. 2 is a rear perspective view of FIG. 1;

FIG. 3 is a side view of FIG. 1;

FIG. 4 is a bottom view of FIG. 1 with the bottom plate removed;

FIG. 5 is a top view of FIG. 1 with the top plate removed;

FIG. 6 is an opposite side view of FIG. 3;

FIG. 7 is an alternate side view of FIG. 6;

FIG. 8 is an opposite alternate side view of FIG. 7;

FIG. 9 is an exploded bottom perspective view of FIG. 1; and,

FIG. 10 is an exploded top perspective view of FIG. 1. The broken line portions of the drawings depict environmental subject matter only and form no part of the claimed design.
